UNITED STATES PATENT OFFICE

113,775

DESIGN FOR AN AIRPLANE

Michael Watter, Baltimore, Md., assignor to The
Glenn L. Martin Company, Baltimore, Md.

Application November 4, 1937, Serial No. 72,616

Term of patent 14 years

To all whom it may concern:

Be it known that I, Michael Watter, a citizen of the United States and resident of the city of Baltimore, in the State of Maryland, have invented a new, original, and ornamental Design for an Airplane, of which the following is a specification, reference being had to the accompanying drawings, forming part thereof.

Figure 1 is a front elevational view of the present

airplane showing the wing floats in restricted position,

Figure 2 is a side view in elevation of Figure 1, and

Figure 3 is a plan view of Figure 1.

I claim:

The ornamental design for an airplane, substantially as shown.

MICHAEL WATTER.
